United States Patent Office

Des. 197,719
Patented Mar. 17, 1964

197,719

VASE

Orville C. Hamon, Cedars, Okla.

(P.O. Box 813, Fort Smith, Okla.)

Filed May 3, 1963, Ser. No. 74,743

Term of patent 14 years

(Cl. D29—28)

I claim:

The ornamental design for a vase, substantially as shown.
